UNITED STATES PATENT OFFICE.

DELOS W. GITCHELL, OF MIDDLETOWN, NEW YORK.

METHOD OF LURING OR LUSTERING HATS.

SPECIFICATION forming part of Letters Patent No. 373,889, dated November 29, 1887.

Application filed April 4, 1887. Serial No. 233,581. (No model.)

To all whom it may concern:

Be it known that I, DELOS W. GITCHELL, of Middletown, in the county of Orange and State of New York, have invented a new and useful 5 Improvement in the Method of Luring or Lustering Hats, of which the following is a specification.

Felt hats are commonly, before ironing, subjected to a luring or lustering operation, in 10 order to lay the nap and give the hat a better appearance when ironed. This luring or lustering has commonly been done by a stationary surface held against the revolving hat.

In carrying out my invention, I subject the 15 hat, while being slowly revolved, to the action of a rapidly-rotating luring-surface against which the hat is held; and my invention consists in an improvement in the method of luring the under side of a hat-brim, consisting in 20 producing a rubbing action across the face or under side of the brim in a direction from the center outward.

By the above-referred-to method of luring or lustering hats a better finish is given the hat 25 than has been heretofore possible, and as the under side of the brim is a part which is felt closely and inspected by purchasers, my improvement renders the hat more salable.

In carrying out my invention, I may employ 30 a machine or apparatus similar to that which forms the subject of my application for Letters Patent, Serial No. 233,580, filed April 4, 1887, and which is shown in the accompanying drawings, wherein—

35 Figure 1 is a side elevation, and Fig. 2 a plan, of the machine.

Similar letters of reference designate corresponding parts in both figures.

A A' designate feed-rolls, by which the brim 40 of the hat is fed slowly in a circular or nearly circular path, the whole hat being rotated or turned, and these rollers are mounted upon shafts B B'. The rollers herein represented are made in the form of frusta of cones, and 45 in order to bring their feeding-surfaces into proper relation the shafts B B' diverge from the rollers toward the opposite ends of the shafts. The shafts B B' may be connected by gear-wheels B², to provide for the synchronous 50 rotation of the rollers A A', and motion may be imparted to both feed-rolls by a belt passing over a driving-pulley, B², on the upper roll-

shaft, B. The lower roll-shaft, B', I have represented as journaled in bearings b in the lower fixed frame portion, C, and in order to provide 55 for varying the distance apart of the roll-surfaces I have represented the upper roll-shaft, B, as journaled in bearings b' in an adjustable upper frame portion, C', which is here represented as hinged at c near the feed-rolls, and 60 is at its outer end adjustably connected with the main lower frame portion, C, by a bolt and nuts c' c², or other suitable means. By raising or lowering the end of the upper frame portion, C', at which is the bolt c', I may vary the press- 65 ure which the feed-rollers exert upon the hat.

D designates a wheel mounted upon a shaft, D', which is journaled in bearings d, and arranged to rotate at the side of the feed-rollers A A' and in a plane substantially parallel 70 with the axes of said rollers. The wheel D has a luring or lustering surface, d², and may be driven at a rapid speed of rotation by a belt passing onto a pulley, d'. The luring or lustering surface d² may be of wool, fur, silk, 75 or other material, according to what is best adapted for the quality of hat to be operated on. As the feed-rollers, by gripping the brim of the hat, which is shown in dotted outline, move the hat in a circular or approximately 80 circular path, the luring-wheel D exerts a luring action upon the under side of the brim and in a direction outward from the center or substantially radial to the hat. This rubbing action exerted by the wheel D serves to lay the 85 nap on the under side of the brim toward the outer edge of the brim and enables the hat to be given a better finish in ironing. It is obvious that the hat might be slowly moved or revolved by hand over the luring-wheel D with 90 good results.

In order to render the wheel D more effective in its action upon the hat, I have represented a pad, E, which may be faced with material similar to the surfacing material d² of the wheel. 95 This pad, as is here shown, is secured upon the end of a lever, E', which is fulcrumed at e to a post, E², and by means of a rod, E³, and treadle E⁴, which is below the bed or table or bench G, the lever may be drawn downward, 100 so as to press the pad E strongly upon the hat-brim to press the hat-brim against the wheel D. The rod E³ works through a guide, e', upon the post E², and when not drawn down by the

treadle E⁴ the lever and pad E'E are lifted by the spring e².

I have here made no claim to the machine shown, as it forms the subject of my above-5 referred-to application for Letters Patent.

What I claim as my invention, and desire to secure by Letters Patent, is—

The improvement in the method of luring the under side of a hat-brim, consisting in

producing a rubbing action across the face or 10 under side of the brim in a direction from the center outward, substantially as herein described.

DELOS W. GITCHELL.
